CLAIM

I claim the ornamental design for a sealable wave bag, substantially as shown and described.

DESCRIPTION

FIG. 1 is a front right perspective view of a sealable wave bag in accordance with the present design.

FIG. 2 is a front view of the sealable wave bag of FIG. 1, the rear view being a mirror image thereof.

FIG. 3 is a right side view thereof, the left side view being a mirror image thereof.

FIG. 4 is a top view thereof.

FIG. 5 is a bottom view thereof.

FIG. 6 is an interior view of a front sheet-like panel, taken along the plane of the line 6-6 in FIG. 3.

FIG. 7 is an interior view of a rear sheet-like panel, taken along the plane of the line 7-7 in FIG. 3.

FIG. 8 is a top plan view of the sealable wave bag of FIG. 1, in a folded-over opened position, and illustrating content, shown in broken lines, contained in the opened sealable wave bag.

FIG. 9 is a front right perspective view of the sealable wave bag of FIG. 1, illustrating the sealable wave bag in an opened position, and illustrating content, shown in broken lines, as well as partial removal of a protective cover over an adhesive seal.

FIG. 10 is a front right perspective view of the opened sealable wave bag of FIG. 9, illustrating the sealable wave bag in a closed, sealed condition.

FIG. 11 is a front elevation view of the sealed wave bag of FIG. 9.

FIG. 12 is a right side elevation view thereof; and,

(Continued)

FIG. 13 is a front right perspective view of the sealable wave bag of FIG. 10, illustrating the front and rear handle flaps removed from the remaining wave bag, via perforations, to access the contents therein.

The broken lines in the Figures show portions of the sealable wave bag which form no part of the claimed design. The shade lines in the Figures show contours and not surface ornamentation.
